UNITED STATES PATENT OFFICE.

JOHN A. WERNER, OF DAYTON, OHIO, ASSIGNOR, BY MESNE ASSIGNMENTS, TO THE NATIONAL CASH REGISTER COMPANY, OF DAYTON, OHIO, A CORPORATION OF MARYLAND.

TOTAL-PRINTING MECHANISM FOR CASH REGISTERS.

Application filed August 16, 1915, Serial No. 300,775. Renewed May 29, 1919.

This invention relates to accounting machines and the like and more particularly to the total printing mechanism therefor.

One object of this invention is to construct 5 improved means whereby the differential mechanism is controlled by manipulative means upon adding operations of the machine and by the totalizer upon total printing operations of the machine.

10 Another object of the invention is to provide a novel arrangement of type carriers, adapted to print items entered in the totalizer, and additional type carriers which are of higher orders and operated during 15 adding operations by the totalizer element of highest order when transfers from the latter are required, the latter type carriers together with the former being adapted to print totals.

20 A still further object of the invention is to turn the totalizer elements to zero and to provide means for turning to zero the additional type carriers of higher orders.

Still another object of the invention is 25 to construct the impression means so that the additional type carriers of higher orders only print on the record material during total printing operations of the machine.

With these and incidental objects in view, 30 the invention consists in certain novel features of construction and combinations of parts, the essential elements of which are set forth in appended claims, and a preferred form or embodiment of which is 35 hereinafter described with reference to the drawings which accompany and form part of the specification.

Of said drawings:

Fig. 1 is a central transverse sectional 40 view through the machine of the type shown in Letters Patent of the United States to Cleal and Reinhard, 580,378, issued April 13, 1897, with the improvements applied.

Fig. 2 is a detail side view of the mechanism for operating the devices to couple 45 the totalizer elements with the differential means.

Fig. 3 is a detail view of one of the banks 50 of keys and the means for controlling total printing operations of the machine. The left hand side frame of the machine, which is between the key bank and the means for controlling the total printing operations of

the machine, has been omitted from this figure to clearly expose the key bank to view. 55

Fig. 4 shows enlarged detail views of the means for shifting the shaft carrying the totalizer coupling pinions, this means being shown in front elevation in the left hand view and in side elevation in the right hand view.

Fig. 5 is an enlarged top plan detail view of one of the totalizer units and its actuating mechanism.

Fig. 6 is an enlarged detail sectional view 65 through one of the totalizer units.

Fig. 7 shows enlarged detail face and edge views of the device whereby a totalizer element is rotated backwardly by the differential mechanism during total printing operations 70 of the machine.

Fig. 8 is an enlarged longitudinal section through one of the totalizer elements and the gears associated therewith.

Fig. 9 is an enlarged top plan detail view 75 of part of the mechanism shown in Fig. 5.

Fig. 10 is an enlarged front view of the printing mechanism.

Fig. 11 is an enlarged detail side view of the additional type carriers of higher orders 80 and the actuating mechanism therefor.

Fig. 12 is a detail longitudinal sectional view through the additional type carriers of higher orders.

Fig. 13 is a detail side view of one of the 85 additional type carriers of higher orders.

Fig. 14 shows enlarged detail views of the operating pawls for the additional type carriers of higher orders.

Fig. 15 is a detail view showing part of 90 the means for turning the additional type carriers of higher orders to zero position.

Fig. 16 is a detail sectional view through the printing mechanism taken on the line A—A of Fig. 10.

Fig. 17 is a detail view showing the type carrier for printing characters designating the classes of transactions.

Fig. 18 is a detail view showing a portion 100 of the detail strip printed on by the machine.

Described in general terms, the machine comprises several banks of manipulative devices which control the differential movement of actuating segments or devices, the latter, in turn, operating the indicating and 105 registering mechanisms. The actuating seg-

ments are coupled to the driving mechanism by latches which, in adding operations, are operated by contact with the keys to disconnect the actuating segments from the 5 driving mechanism. Each actuating segment, through intermediate gears and pinions, imparts its differential movement to two gears associated with the appropriate totalizer element, the two gears being rotated in opposite directions. In adding operations, the totalizer elements are each connected by broad pinions to that one of the two gears which rotates in the adding direction so that the items set up on the 10 keys are accumulated on the totalizer. Preliminarily to operation of the machine for printing a total, the broad pinions are shifted so that they operate to couple the 15 totalizer elements with the gears which are reversely rotated upon differential movement of the actuating segments from zero position to restore the totalizer elements to zero. The totalizer elements, upon reaching 20 zero positions, control mechanism which operates the above mentioned latches to disconnect the actuating segments from the 25 driving mechanism.

Type carriers are differentially positioned in accordance with the amount set up on 30 the keys in adding operations and in accordance with the amount standing on the totalizer elements in total printing operations. The totalizer element of highest order actuates additional type carriers when transfers 35 from the highest order totalizer element are necessary, no banks of amount keys being provided for these additional type carriers. The impression means is so constructed that upon adding operations only, the type carriers controlled by the depressed keys print 40 upon the detail strip. When a total is to be printed, however, the impression means is adjusted by the means for preparing the machine for total printing operations so 45 that upon operation of the impression means during the operation of the machine the type carriers, controlled by the keys during adding operations and by the totalizer elements in total printing operations, together 50 with the above mentioned additional type carriers, print the totals accumulated on the totalizer. When the means for preparing the machine for total printing operations is manually restored to normal position 55 after the machine is operated, this means actuates a device for resetting the additional type carriers to zero.

Manipulative devices, such as keys 20 (Figs. 1 and 3), are arranged in groups or 60 banks and when depressed against the tension of their springs, are latched in depressed positions by detents 21, there being one detent for each bank of keys. The forward ends of the detents 21 are elevated when keys 65 are depressed, and the detents are locked

in elevated positions during the operation of the machine by latch plates 17 (Fig. 1) moved rearwardly by their springs 18 to carry their shoulders 19 under the forward ends of the detents 21 when the detents are 70 elevated. Each detent 21 is provided with a stud 22 which engages the forward end of a corresponding arm 23 fast on a shaft 99 so as to rock this shaft against the influence of a spring 25, connected at its upper end to 75 one of the arms 23 and at its lower end to a shaft 34. The shaft 99 extends horizontally through the machine and is provided at its right hand end with a rearwardly extending arm 26 which has, at its extreme 80 rearward end, a vertical projection normally engaging a recess 27 formed in the periphery of a disk 28 fast on a shaft 29. A main drive shaft 30 is given one complete rotation counter-clockwise (Fig. 1) by a crank 85 handle or other desired means upon each operation of the machine, and the shaft 29 is given one complete rotation in a clockwise direction (Fig. 3) upon each operation of the machine, by the shaft 30 through suitable gearing (not shown). From this description it can be seen that the operating mechanism will be locked against operation by the arm 26 until one of the keys is depressed to move the projection on the arm 26 90 out of the recess in the disk 28.

Rigidly mounted on the shaft 30 is a crank 31 (Fig. 1) connected by a link 32 to an arm 33 fast on the shaft 34. As the crank 31 is shorter than the arm 33, the rotation of the 100 shaft 30 rocks the shaft 34 first counter-clockwise as viewed in Fig. 1, about 90 degrees and then clockwise to normal position. Fast on the shaft 34 are driving segments 36, one for each bank of keys. When 105 the shaft 34 and the segments 36 are rocked counter-clockwise, shoulders 37 formed on the segments will be engaged by projections on the rear ends of latches 38 when the shoulders are brought opposite the projections. The latches 38 are pivotally hung by links 39 on actuating segments 40 loosely mounted on the shaft 34. Bell cranks 420 are pivoted at 421 to the respective actuating segments 40 at points adjacent the 110 respective latches 38, one arm of each bell crank being pivotally connected by a pin 41 to its latch, and the remaining arm of each bell crank carrying a spring-pressed pawl 42 pivoted thereto and projecting beyond the path of travel of its actuating segment 40. Upon return clockwise of the segments 36, the actuating segments 40 carrying the latches 38 of the banks in which 115 keys are depressed, will be carried with the segments 36 distances determined by the value of the keys depressed, the inner ends of the depressed keys lying in the paths of the pawls 42 to arrest the latter, the effect being to draw the latches 38 forwardly and 120 125 130

thereby disconnect the driving segments 36 from the actuating segments 40. Projections 35 on the latch plates 17 (Fig. 1) appropriate to the banks of keys in which 5 no keys are depressed, engage the pins 41 on the latches 38 and if the actuating segments 40 are already in zero positions, prevent the latches from being operated to connect the actuating segments 40 and driving 10 segments 36. If an actuating segment 40 has been moved out of zero position at the preceding operation of the machine, its latch 38, when moved to zero position, is operated by the projection 35 on the latch 15 plate 17 if a key in the corresponding bank is not depressed, and therefore, the actuating segment is disconnected from its driving segment 36. Near the end of the operation of the machine, the operated latch plates 20 17 are restored to their normal positions by the segments 36. This construction is well known in the art and is fully shown and described in the above mentioned patent to Cleal and Reinhard, and therefore has not 25 been described in detail here.

The actuating segments 40 are provided with teeth 44 which mesh with gears 45, these gears in turn, meshing with smaller gears 46 secured to indicators 47 mounted 30 loosely upon a transverse rod 48.

The gears 45 also mesh with gears 49 (Figs. 1, 5, and 8) rigidly connected by pins 50 (Fig. 8) to gears 51 loosely mounted on sleeves 52, rotatable on a shaft 53. Totalizer elements or disks 54 are integral with the sleeves 52 and are connected to gears 55, adjacent the gears 51, by pins 56. The totalizer disks 54 do not have the usual numerals on their peripheries, but these numerals may be placed thereon if desired 35 and may be viewed through openings in the cabinet. In the illustrative form shown in the drawings, however, these numerals have been omitted as the total accumulated on the 40 totalizer elements is printed upon total printing operations. The gears 51 and 55 are normally disconnected and just previous to the clockwise movement (Fig. 1) of the actuating segments 40, they are connected 45 by broad pinions 59 (Figs. 1 and 5), there being one pinion for each totalizer disk 54, so that the differential movement of the actuating segments 40 will be imparted to the totalizer disks 54 through gears 45, 50 49, 51, 55, and pinions 59. These broad pinions 59 are mounted in the upper ends 55 of arms 60 secured to a shaft 61. A downwardly extending arm 63 (Fig. 2) is splined on the shaft 61 so that the shaft 61 rocks 60 with the arm, but may be shifted laterally independently of the arm. The lower end of the arm 63 is pivotally connected to the forward end of a pitman 64 which, at its rear end, is forked to embrace the drive 65 shaft 30 and carries a roller projecting into

a cam groove formed in the face of a disk 67 fast on the shaft 30. The shape of the cam groove in the disk 67 is such that just before the actuating segments 40 begin their clockwise movements (Fig. 1) from zero 70 positions, the pitman 64 will be thrust forwardly (to the left in Fig. 2) to rock the broad pinions 59 into engagement with the corresponding pairs of pinions 51 and 55 to connect them for movement together. The 75 actuating segments 40 are moved counter-clockwise to their zero positions at the beginning of each operation of the machine by extensions or flanges 68 on the segments 36 which contact the actuating segments 40 so and rock them counter-clockwise to their normal positions. During this movement of the actuating segments, the broad pinions 59 are out of mesh with the gears 51 and 55.

Any suitable transfer mechanism may be 80 employed. None is shown, as it is not essential to an understanding of this invention.

The gears 45 are fast on the right hand ends of nested sleeves 70 (Figs. 1, 10 and 16), which surround the shaft 29, and the opposite ends of the sleeves carry printing segments 71 for recording items and totals upon a detail strip 72 (Figs. 16 and 18). The detail strip is fed from a supply roll 73 over platens 74 and 75 (Fig. 10) and thence to a storage roll 76 (Fig. 16). The detail strip is carried on a frame 77 having an arm 78 (Fig. 10) slidably mounted in a stationary frame 79 mounted on the left 100 hand side frame of the machine. The platens 74 and 75 are fast on a shaft 80 journaled in the frame 77. The arm 78 carries a roller 82 (Fig. 10) projecting into a cam groove formed in a disk 83 rigidly 105 mounted on the shaft 29. The shape of the cam groove in the disk 83 is such that, upon rotation of the shaft 29, the frame 77 carrying the platens and the detail strip will be first lowered to feed the detail strip and 110 permit the inking of the type carriers and then be raised to take an impression upon a check strip, after which it is lowered to permit the ejection of the check and is finally raised to take an impression upon the detail 115 strip 72. The previously mentioned check strip is not shown in the present drawings, it being sufficient to state here that it is fed over the platen 74 so that when the platen 74 is first raised, an impression will be taken 120 from the type carriers and a portion of the check strip will be severed whereupon a check ejector 84 (Fig. 16) grips the check and ejects it from the machine as the frame 77 is lowered. Previous to the printing of 125 the check, an ink pad 85 carried by an arm 86 is rocked to ink the adjusted type and is then moved out of the path of the platen 74.

The operation of the machine so far described is practically the same as that shown 130

and described in the above mentioned Cleal and Reinhard patent. The improvements applied to this type of machine will now be described in detail, but it is to be understood that these improvements are not to be limited to the particular type of machine to which, for illustration, they have been shown as applied.

Rigidly mounted on the gears 45 are circular plates or racks 88 (Fig. 1) having on their outer peripheries a set of teeth 89, a set of teeth 90 and V-shaped aligning notches 91. The teeth 89 and 90 of each plate 88 mesh with a corresponding pinion 92 rigidly connected by its hub 93 (Figs. 5 and 7) to a pinion 94. The pinions 92 and 94 are loosely mounted on a cross rod 95 projecting through the machine. Each pinion 94 meshes with a gear 96 (Figs. 5 and 20) loosely mounted on the hub of the corresponding gear 55. Through these connections the differential movements of the actuating segments 40 are imparted to the gear wheels 96, the direction of movement of the gear wheels 96 being reverse to that of the gear wheels 49 and 51. In adding operations the broad pinions 59 only mesh with the pairs of gears 51 and 55 so that the gears 96 rotate idly upon the hubs of the gears 55. 25 When a total is to be printed, the shaft 61, and therefore the broad pinions 59, are shifted towards the left preliminarily to the operation of the machine, as will be presently described, so that when the shaft 61 is 30 rocked by the cam 67 (Fig. 2), the broad pinions will mesh with the pairs of gears 55 and 96 but not with the gears 51, and therefore, the gears 49 and 51 are idly rotated during total taking operations of the machine. As the gear wheels 96 are rotated 35 reversely to the gear wheels 51 by the actuating segments 40 through the gears 45 and pinions 92 and 94, the totalizer disks 54 are rotated reversely to their zero positions 40 when the pinions 59 are moved into engagement with the gears 55 and 96 during total printing operations.

When the totalizer disks 54 reach their zero positions, the latches 38 (Fig. 1) are operated to disengage the actuating segments 40 from their driving segments 36. The means for effecting this disconnection of the actuating segments from their driving segments under the control of the totalizer disks will now be described.

Loosely mounted on the shaft 99 are a number of arms 100 (Figs. 1, 6 and 9), one for each of the totalizer disks 54. The arms 100 are held against lateral movement 60 on the rod 99 by collars 106. Springs 101 connected at their lower ends to the forward ends of the arms 100 and at their upper ends to a cross rod 102, normally retain the upper edges of the arms 100 in contact 65 with the shaft 61. The arms 100 carry studs

103 which project through slots 104 in the corresponding levers 105. The studs 103 are so constructed that the levers 105 are prevented from moving laterally of the arms 100. The shaft 61 projects through recesses 70 107 formed in the levers 105, the latter being slidably mounted on the shaft 61 and the studs 103 so that they can be moved rearwardly. The shaft 61 is also free to be shifted independently of the levers 105. 75 When the shaft 61 is shifted to move the pinions 59 into position to engage the pairs of gears 55 and 96 during total printing operations, hubs 108 (Figs. 5 and 6) integral with the pinions 59, are moved in front of 80 the vertical arms of the levers 105 so that when the shaft 61 is rocked to move the pinions 59 into mesh with the pairs of gears 55 and 96, the hubs 108 contact the levers 105 and slide the latter rearwardly on the shaft 85 61 and the studs 103. Projecting laterally from the totalizer disks 54 are pins 110 which, when the totalizer disks approach their zero positions during total printing operations contact shoulders 111 on the levers 105 to rock the levers clockwise (Fig. 6) about the shaft 61. During adding operations the levers 105 are not moved rearwardly, and therefore the pins 110 on the totalizer disks do not strike the shoulders 90 111. 95

When one of the levers 105 is rocked clockwise (Fig. 6) by the pin 110 on the corresponding totalizer disk, as above described, it rocks the corresponding arm 100 100 counter-clockwise, as the stud 103 on the arm projects through the slot 104 in the lever 105. When the arm 100 is rocked in this manner, its downwardly extending projection or foot 113 is moved into the path of movement of one of the shoulders 114 formed on a sliding arcuate plate 115. Each plate 115 is slidably mounted on the corresponding actuating segment 40 by pins 116 which project from the actuating segment through 105 slots in the plate 115. A spring 117, which is connected at its forward end to a hook 118 on the plate 115 and at its rear end to a pin on the actuating segment 40, serves to retain the plate 115, relatively to the segment 40 in the position shown in Figs. 1 and 6. When the projection 113 of the arm 100 is moved into the path of movement of one of the shoulders 114 on the plate 115, the shoulder engages the projection, thereby 110 arresting the plate 115, while the segment 40 is permitted to move slightly further, this additional movement being permitted by slot and pin connections between the segment 40 and the plate 115. During this 115 slight additional movement of the segment 40, the pawl 42 (Fig. 1) contacts the lower end of the plate 115 to cause the latch 38 to disconnect the actuating segment 40 from the driving segment 36. From this con- 120 125 130

struction it can be seen that when a totalizer disk 54 arrives at zero position during total printing operations of the machine, the corresponding actuating segment 40 is positively arrested under the control of the totalizer disk, the segment having moved an extent commensurate with the amount standing on the totalizer disk at the beginning of the operation of the machine. Movement of the actuating segments, under the control of the totalizer, positions the type segments 71 as in adding operations, to print the total standing on the totalizer disks. The additional movement of the segments 40 relatively to the plates 115 is very slight, being just sufficient to effect the operation of the latches 38. This additional movement moves the totalizer disks 54 slightly past zero position and the type segments slightly past their proper printing positions, but movement of the forward ends of the latches 38 into the aligning notches 119 moves the actuating segments, the type segments and totalizer disks back to their proper positions.

When the broad coupling pinions 59 are rocked out of engagement with their corresponding pairs of gears 55 and 96, springs 120 (Fig. 6) connected at one end to the rod 102 and at their opposite ends to the levers 105, serve to draw the levers forwardly to their normal positions. At the same time, the springs 101 restore the arms 100 to their normal positions, thereby moving the projections 113 out of engagement with the shoulders 114 on the plates 115, whereupon the springs 117 move the plates 115 to their normal positions relatively to the actuating segments 40.

The V-shaped ends of aligning arms 122 (Fig. 1) fast on a shaft 1123, engage the notches 91 or between the teeth 90 to align the gears 45, and therefore, the indicators and the type segments in adjusted positions while impressions are being taken from the latter. In case movement of the forward ends of the latches 38 in the notches 119 fails to move the actuating segments 40 and gears 45 back to their proper positions after they have been given the above mentioned additional movement in total printing operations, the arms 122 will accomplish this return movement when moved into aligning positions. The shaft 1123 is rocked by means which is not shown in the drawings but well known in the art, to move the aligning arms 122 into and out of aligning positions at the proper times. The pinions 92 (Figs. 1 and 7) have several alternate teeth cut away so that the pinions may properly mesh with the teeth 90. Each pinion 92 is also provided with a recess 123 so that it may pass over the foremost tooth 90, which tooth is enlarged to contact the aligning arm 122 if the actuating segment 40 should be overthrown slightly past zero position,

whereby overthrow of the differential mechanism past zero is prevented. It is understood, of course, that when the aligning arm is out of aligning position it is still in position to be engaged by the enlarged tooth 90.

In order to align the totalizer disks 54 in their proper positions during adding operations of the machine and to prevent reverse movement of the disks during such operations, the lower ends of levers 125 (Fig. 6), 75 loosely mounted on the rod 95 co-operate with ratchets 126 fast on the sleeves 52 integral with the totalizer disks. Compressed springs 127 serve to retain the levers 125 in engagement with the ratchets 126. For the purpose of rocking the levers 125 out of engagement with the ratchets 126 during total printing operations to permit backward movement of the totalizer disks, arms 128 fast on the shaft 61 co-operate with arms 129 fast on the levers 125. As shown in Fig. 9, the arms 128 normally do not project over the arms 129 and therefore, during adding operations, the arms 128 are rocked 80 idly with the shaft 61. When the shaft 61 90 is shifted preliminarily to total printing operations, the free ends of the arms 128 are moved over the free ends of the arms 129 so that when the shaft 61 and the arms 128 are rocked, the levers 125 are disengaged 95 from the ratchets 126.

The means for shifting the shaft 61 to prepare the machine for total printing is shown in Figs. 3 and 4, and will now be described. A lock 131 having any desired 100 construction, is rigidly mounted on the right hand side frame of the machine, and a ratchet segment 132 secured to the key barrel 133, carries a pin 134 projecting into a slot 135 formed in a lever 136 loosely mounted at 137 on the right hand side frame of the machine. The rearwardly and downwardly extending arm of the lever 136 is pivotally connected to the upper end of a link 137 which, at its lower end, is pivotally connected to a lever 138 also pivotally mounted on the right hand side frame of the machine. The link 137 intermediate its ends has a projecting arm 1381 provided with a recess into which projects 110 a knob 139 formed on the right hand side arm of a yoke 140 loosely mounted on the shaft 61. The left hand side arm of the yoke 140 is provided with a slot 141 concentric with the shaft 61 and a pin 142 projecting from the right hand side frame of the machine projects through the slot. The yoke 140 carries a roller 143 projecting into a cam groove 144 formed in the periphery of a segment 145 rigidly mounted on the 115 shaft 61 within the yoke.

When a key is inserted in the key barrel 133 and given one-half rotation in a clockwise direction (Fig. 3), the movement of the pin 134 in the slot 135 rocks the lever 130

136 counter-clockwise, thereby elevating the link 137. The elevation of this link rocks the yoke 140 counter-clockwise. The cam groove 144 in the segment 145 is so shaped 5 that when the yoke 140 is rocked, as above described, movement of the roller 143 in the cam groove 144, shifts the shaft 61 towards the left to move the broad coupling pinions 59 into position to be rocked 10 into mesh with the corresponding pairs of gears 55 and 96. When the yoke 140 is rocked, movement of the roller 143 in the cam groove 144 tends to shift the yoke towards the right on the shaft 61, but such 15 shifting movement of the yoke is prevented by the head of the pin 142 which projects from the frame of the machine through the slot 141 in the yoke. After a total has been printed, the above described mechanism is 20 restored to normal position by turning the key in the key barrel 133 counter-clockwise (Fig. 3) one-half rotation to normal position.

It is usual in the art to provide a number 25 of totalizer elements which are of higher orders and for which no banks of amount keys are provided, these additional totalizer elements being operated by the transfer mechanism when transfers from the totalizer wheel of highest order appropriate to the bank of amount keys of highest order moves from its "9" to its "0" position. These 30 additional totalizer elements usually control differential units similar to those controlled by the banks of amount keys in total printing operations so that the amount standing on these higher order totalizer wheels is transferred to additional type wheels. In 35 the present invention, instead of providing additional totalizer elements whose amounts are transferred to additional type wheels in total printing operations, the totalizer wheel of highest denomination transfers directly to additional type wheels which, in the 40 present form or embodiment, do not print upon the detail strip or check strip during adding operations.

The above mentioned additional type carriers are in the form of type wheels 146 (Figs. 10 to 13, inclusive) positioned to rotate on a sleeve 147 surrounding a stud 148 mounted in the left hand side frame of the machine. Loosely mounted on the stud 148 is a yoke frame 149 carrying a pivoted pawl 55 150 (Figs. 11 and 14) provided with operating tines co-operating with the ratchet wheels 152 fast to the type wheels 146. The construction of this operating means for the type wheels is well understood and known in the art, "one" being added on the lower order type wheel 146 each time the yoke frame 149 is oscillated about the stud 148. When said lowest order wheel 146 passes 60 from "9" to "0" the graduated pawl 150 causes "1" to be added into the next higher order wheel 146. Aligning levers 154 retained in engagement with the ratchet wheels 152 by spring-pressed plungers 155 serve to prevent retrograde movement of the type wheels. The left hand side of the yoke 70 frame 149 has a recess 156 into which a pin on the lower end of an arm 158 projects. The arm, near its upper end, is loosely mounted on a pin 159 projecting from an arm 160 of the left hand side frame of the 75 machine. The arm 158 also carries a roller 161 which projects into a cam groove formed in the face of a disk 162 rigidly mounted on the left hand end of a sleeve 163 mounted to rotate about the shaft 53. The left hand 80 end of the sleeve 52 of the totalizer disk 54 of highest order has a tenon 164 (Fig. 10) engaging a recess in the right hand end of the sleeve 163, the sleeve 163 and the sleeve 52 for the totalizer wheel of highest order 85 being connected together in this manner so that the rotation of this totalizer wheel is imparted to the disk 162. The cam groove in the disk 162 is so constructed that, as the totalizer disk of highest order passes 90 from its "9" to its "0" position, the arm 158 is rocked, first counter-clockwise (Fig. 11) and then clockwise to normal position. This movement of the arm 158 oscillates the yoke frame 149 to effect transfers from the 95 totalizer wheel of highest order to the printing wheels 146.

In the Cleal and Reinhard patent above mentioned, the printing segment for printing characters designating the classes of 100 transactions is immediately adjacent the highest order amount type segment. As the type wheels 146 in the present invention print the amounts in the denominations of higher order than those of the type segments 105 71, the segment 168 (Figs. 10 and 17) for printing characters designating the classes of transactions is positioned to the left of the units type segment 71. This type segment 168 is connected by a bar 169 to a 110 collar 170 rigidly mounted on the outermost sleeve 70 which is differentially positioned by the bank of transaction keys (not shown) through a segment gear (not shown) which meshes with a gear 172 fast on this outermost sleeve, as is well known in the art.

As the items entered in the machine are set up only on the amount type segments 71, and as the totals are set up on the amount segments 71 and the additional type wheels 120 146, it is desirable to print only from the type segments 71 in adding operations, and from these type segments and the additional type wheels 146 in the total printing operations. In order to prevent the additional type wheels 146 from printing on the check and the detail strip in adding operations, the platen 75 is cut away from its circular periphery to the line 174 (Figs. 10 and 16) so that when the frame 77 carrying the 125 130

platens is elevated, the platen 75 does not engage the detail strip and therefore, the latter is not pressed into contact with the type wheels 146. When a total is to be printed, however, the shaft 80 upon which the platens 74 and 75 are rigidly mounted, is given one-quarter rotation preliminarily to the operation of the machine so that when the frame 77 is raised during the operation 10 of the machine, the circular periphery of the platen 75 engages the detail strip to carry the latter against the additional type wheels 146 and thereby effect printing impressions. For the purpose of rocking the shaft 80, an arm 175 is rigidly mounted on the shaft and near its free end carries a roller 176 projecting into a slot formed in the lower end of a link 177 which, at its upper end, is pivotally mounted on a segment gear 178 fast on the shaft 53. At its right hand end, the shaft 53 rigidly carries a disk 180 (Fig. 3) having teeth 181 engaging a curved set of teeth 182 formed on the forward edge of the link 137. When the link 137 is raised, as above described, the shaft 53 is rocked counter-clockwise (Figs. 3 and 16) through the intermeshing teeth 181 and 182, thereby rocking the segment gear 178 which, through the link 177 and 30 the arm 175, rocks the shaft 80, as above stated.

When the mechanism shown in Figure 3 for controlling the machine for total printing operations is manually restored to normal position, the additional type wheels 146 are restored to their zero positions. For the purpose of turning these type wheels to their zero positions, the segment gear 178 meshes with a pinion 185 (Figs. 12, 15 and 16) fast on the sleeve 147 upon which are loosely mounted the type wheels 146. The type wheels, as shown in Figure 13, carry spring-pressed pawls 186, the ends of which rest on the sleeve 147. The sleeve 147 has a longitudinal groove 187 which, when the sleeve 147 is rotated clockwise (Fig. 13) by the return movement of the segment gear 178 to normal position, engages the ends of the pawls 186 in whatever positions the wheels are standing and restores the wheels to their zero positions as is well known in the art. When the segment gear 178 is rocked clockwise, as viewed in Figure 15, when the machine is prepared for total printing operations, the sleeve 147 is rotated counter-clockwise, as viewed in Figures 13 and 15, and during such rotation, the groove 187 moves idly past the pawls 186. When the segment gear 178, however, is rocked in the reverse direction after a total printing operation has been accomplished, the sleeve 148 is rocked in reverse direction whereby the type wheels are restored to their zero positions, as above described.

As the differential mechanism is con-

trolled by the totalizing disks 54 during total taking operations, it is necessary that none of the amount keys be depressed and therefore, the following described means is employed to lock the keys against depression when the machine is prepared to print a total. This means comprises key lock-out bars 190 (Fig. 3), there being one bar for each bank of keys. The bars are slidably mounted at their upper and lower ends, 75 and are therefore, at the upper ends provided with slots 191 through which pins on the key frames project, and at their lower ends, with slots 192 through which a cross rod 193 projects. The bars 190 at their lower ends carry pins 194 which contact arms 195 fast on a shaft 196. Fast on the shaft 196 is a lever 197, which may be operated at any time before the machine is operated, to rock the shaft 196 counter-clockwise 85 (Figs. 1 and 3) and, through pins 203 on the shaft co-operating with pins 204 on the latch plates 17, draw the latter forwardly to effect the release of depressed amount keys, as is well known in the art. Springs (not shown) serve normally to retain the lever 197 and arms 195 in the positions shown in Figure 3. When the link 137 is elevated to prepare the machine for a total printing operation, a prong 198 on the lever 138 engages the rearwardly extending arm 199 of the lever 197, thereby rocking the lever, the shaft 196, and the arms 195 clockwise. This movement of the arms 195 through their contact with the pins 194, elevates the key 100 lockout bars 190 to carry the recesses 200, normally under the pins 201 on the keys, from under the pins thereby locking the keys against depression.

It can be seen that if a key has been depressed, its pin 201 is in one of the recesses 200 and the bar 190 cannot be elevated, and therefore, the machine cannot be prepared for a total printing operation until after the lever 197 has been operated to effect release of the key. When the link 137 is moved downwardly to normal position after a total printing operation, a prong 202 of the lever 138 engages the underside of the arm 199 of the lever 197 to insure the return of this lever, the shaft 196 and the arms 195, to normal positions.

As before stated, when the actuating segments 40 are moved to their zero positions at the beginning of the operation of the machine, the projections 35 on the latch plates 17 (Fig. 1) which have not been moved rearwardly, engage the pins 41 on the latches 38 and disconnect the segments 40 from their driving segments 36. In order 125 to permit operation of all of the plates 17 for the banks of amount keys when the machine is prepared for printing a total, the detents 21 (Fig. 3) are operated, whereupon the springs 18 operate the latch plates 17 130

so that the projections 35 on the latch plates do not engage the pins 41 on the latches 38, the latches in such operations being controlled by the registering disks, as above described. To operate the detents 21, each detent has a pin 205 contacting the upper edge of a toe 206 formed on the lower end of the corresponding lockout bar 190. When the lockout bars 190 are elevated preliminarily to a total printing operation of the machine, as above described, their toes 206 operate the detents 21, whereupon the latch plates 17 are drawn rearwardly by their springs 18, to permit the latches 38 to couple the driving segments 36 and the actuating segments 40. Operation of the detents 21 in this manner, through the engagement of their studs 22 with the arms 23, operates the shaft 99 and the arm 26 to move the arm 26 out of the recess 27 in the disk 28 and permit operation of the machine.

The following described device is employed to compel a complete one-half rotation of the lock barrel 133 (Fig. 3) to prepare the machine for total printing operations after the lock barrel has been partially turned. A lever 209, (Fig. 3) which is pivotally mounted at 208 on the right hand side frame of the machine, at its rear end has a nose 211 engaging under a hook 212 on an arm 213 of a lever 215 pivoted at 216 to the side frame of the machine. A spring 218 is connected at its upper end to the lever 209, and at its lower end to an arm 217 of the lever 215, the spring normally serving to retain the levers 209 and 215 in the positions shown in Figure 3. The forward end of the arm 217 engages the teeth of ratchet segment 132 so that when clockwise movement of the ratchet segment is begun, the arm 217 prevents its return movement to normal position. Furthermore, after the ratchet segment has been given its one-half rotation the machine must first be operated before the ratchet segment can be returned to normal position. During the operation of the machine, the arm 217 of the lever 215 is disengaged from the ratchet segment. A disk 220 fast on the shaft 29 carries a stud 221 which, near the very end of the operation of the machine, engages the free end of the arm 223 of the lever 215 thereby rocking the lever 215 counter-clockwise. When the lever 215 is rocked in this manner, the hook 212 on its arm 213 is moved from above the nose 211 on the lever 209 and the spring 218 rocks the lever 209 so that its nose 211 is moved within the hook 212 and latches the lever 215 in its moved position, wherein its arm 217 is disengaged from the ratchet segment. Near the end of the counter-clockwise movement of the ratchet segment 132 when the ratchet segment is moved back to normal position after the machine has been operated, a pin 224 on the ratchet segment

engages an inclined edge 225 on the lever 209, thereby rocking the latter to its normal position to permit the spring 218 to restore the lever 215 to normal position.

Operation.

70

Having described in detail the construction and operation of the various parts of the present invention, a resume of its operation will now be given.

75

In adding operations the keys are depressed in accordance with the amount of the transaction and upon operation of the machine, the depressed keys arrest the latches 38 to disconnect the actuating segments 40 from their driving segments 36. Before the actuating segments are moved differentially out of zero positions the cam 67 (Fig. 2) moves the broad coupling pinions 59 (Figs. 1 and 5) into mesh with the corresponding pairs of gears 51 and 55 so that the differential movements of the actuating segments is imparted to the totalizer disks 54, through the gears 45, 49, 51, 55, and pinions 59.

90

The movements of the actuating segments are imparted to the type segments 71, and while these type segments are in their moved positions, the frame 77 is operated so that the platen 74 carries the check and the detail strip against the printing line of the type segments to take printing impressions. When the totalizer disk 54 of the highest order (Fig. 10) passes from its "9" to its "0" position, the cam 162 (Fig. 11), through the arm 158, operates the operating frame 149 and pawl 150 to add "one" on the lowest order of the additional type wheels 146.

100

When a total is to be printed, the key barrel 133 (Fig. 3) and the ratchet 132 are given one-half of a rotation and through the lever 136, elevate the link 137. This movement of the link 137 rocks the yoke 140 which, in turn, shifts the shaft 61 towards the left through the movement of the roller 143 in the cam groove 144 formed in the segment 145 fast on the shaft. During the operation of the machine when the shaft 61 is rocked by the cam 67, the pinions 59, having been shifted with the shaft, are moved into engagement with the corresponding pairs of gears 55 and 96 so that the totalizer disks are rotated backwardly. When the pinions 59 are rocked, their hubs 108 (Figs. 5 and 6) engage and move the levers 105 rearwardly to carry the shoulders 111 on the levers into the paths of movement of the pins 110 on the totalizer disks 54. When a totalizer disk approaches its zero position, its pin 110 contacts the shoulder 111 on the lever 105, thereby rocking the latter about the shaft 61 and the corresponding arm 100 about the shaft 99 to carry the projection 113 on the arm 100 into the path of one of the shoulders 114 on the plate 115 carried by 110

115

120

125

130

the actuating segment. Engagement of the shoulder 114 with the projection 113 arrests the plate 115 and permits a slight additional movement of the actuating segment, the lower end of the plate 115 striking the pawl 42 to operate the latch 38 and thereby effect disconnection of the actuating segment and driving segment.

The differential movement of the actuating segments 40 in total taking operations is imparted to the type segments 71 in the same manner as in adding operations. When the link 137 is raised (Fig. 3), the shaft 53 is rocked through the intermeshing 15 teeth 181 and 182, and through the segment gear 178 (Fig. 16), the link 177 and the arm 175, the platens 74 and 75 are rotated so that when the frame 77 is operated during an operation of the machine the platen 75 carries the detail strip against the additional type carriers 146. Thus the complete total is printed, partly from the type segments 71, and partly from the type carriers or wheels 146.

25 After the machine has been operated to take a total, the key barrel 133 and the mechanism operated thereby are restored to normal positions. Movement of the segment gear 178 to normal position, through the pinion 185, rotates the sleeve 147 carrying the additional type wheels, and the sleeve, through the co-operation of its groove 187 with the pawls 186, restores these type wheels to their zero positions.

35 While the form of mechanism herein shown and described, is admirably adapted to fulfil the objects primarily stated, it is to be understood that it is not intended to confine the invention to the one form or embodiment herein disclosed, for it is susceptible of embodiment in various forms all coming within the scope of the claims which follow.

What is claimed is:—

45 1. In a machine of the class described, the combination of a differentially movable actuator, two members moved in opposite directions thereby, a totalizing element, and means for coupling the totalizing element with either of said members, the element being reset to zero whenever coupled with one member and moved to accumulate items when coupled with the other member.

55 2. In a machine of the class described, the combination of a differentially movable actuator, two members moved in opposite directions thereby, a totalizing element, means for coupling the totalizing element with either of said members, the element being reset to zero when coupled with one member and moved to accumulate items when coupled with the other member, and means operated by the totalizing element for limiting the extent of movement of the actuator when 60 the totalizing element is reset to zero.

3. In a machine of the class described, the combination of a differentially movable actuator, a totalizing element, two connections intermediate the totalizing element and the actuator through one of which items are set up, while through the other the totalizing element is reset to zero, means for coupling the totalizing element with either of the two connections, and means operated by the totalizing element for limiting the extent of movement of the actuator when the totalizing element is reset to zero.

4. In a machine of the class described, the combination of a differentially movable actuator, two members moved positively in opposite directions thereby, a totalizing element, means for coupling the totalizing element with either of said members, the element being reset to zero whenever coupled with one member and moved to accumulate items when coupled with the other member.

5. In a machine of the class described, the combination of a differentially movable actuator, two members moved positively in opposite directions thereby, a totalizing element, means for coupling the totalizing element with either of said members, the element being reset to zero when coupled with one member and moved to accumulate items when coupled with the other member, and means operated by the totalizing element for positively limiting the extent of movement of the actuator when the totalizing element is reset to zero.

6. In a machine of the class described, the combination of a differentially movable actuator, two gears moved in opposite directions thereby, a totalizing element, and a broad pinion for coupling the totalizing element with one of said gears to effect addition and for coupling the totalizing element to the other of said gears so that the totalizing element is reset to zero.

7. In a machine of the class described, the combination of a main operating mechanism, a differentially movable actuator moved by the operating mechanism, a totalizing element, gears moved in opposite directions by the actuator, a coupling pinion moved into engagement with either one of said gears during the operation of the machine whereby the totalizing element is moved to effect addition when coupled with one gear, and to be reset to zero when coupled with the other gear, and means for shifting the coupling pinion into position to be moved into engagement with either one of said gears.

8. In a machine of the class described, the combination of a main operating mechanism, a differentially movable actuator moved by the operating mechanism, a totalizing element, gears moved in opposite directions by the actuator, a coupling pinion moved into engagement with either one of said gears

during the operation of the machine whereby the totalizing element is moved to effect addition when coupled with one gear and to be reset to zero when coupled with the other gear, means for shifting the coupling pinion into cooperative relation with either one of said gears, and means for moving the coupling pinion into coupling engagement at the same time in adding operations as in 10 resetting operations.

9. In a machine of the class described, the combination of a main operating mechanism, a differentially movable actuator moved by the operating mechanism, a totalizing element, gears moved in opposite directions by the actuator, a coupling pinion moved into engagement with either of said gears during the operation of the machine whereby the totalizing element is moved to 20 effect addition when coupled with one gear, and to be reset to zero when coupled with the other gear, means for shifting the coupling pinion into cooperative relation with the desired one of said gears, and a device moved into position by the movement of said coupling pinion when the totalizing element is reset so that the device will be operated by the totalizing element for the purpose of controlling the extent of movement of the actuator.

10. In a machine of the class described, the combination of a main operating mechanism, two members driven differentially in opposite directions upon each operation of the machine, manipulative means for controlling the same, a totalizing element, and means for connecting the totalizing element with either of said members during operation of the machine, the element being operated in an adding direction when connected with one of said members and reset to zero whenever connected with the other.

11. In a machine of the class described, the combination of a main operating mechanism, two members driven differentially in opposite directions upon each operation of the machine, manipulative means for controlling the same in adding operations, a totalizing element, means for connecting the totalizing element with either of said members during operation of the machine, the element being operated in an adding direction when connected with one of said members and reset to zero when connected with the other, and means controlled by the totalizing element for limiting the extent of movement of the members when the element is reset.

12. In a machine of the class described, the combination of a main operating mechanism, a differentially movable actuator moved thereby, a totalizing element, two gears moved in opposite directions by the actuator, a coupling pinion moved into engagement with either one of said gears dur-

ing operation of the machine, whereby the totalizing element is moved in an adding direction when coupled with one gear and in the reverse direction to zero when coupled with the other gear, and means for manually shifting said coupling pinion preliminarily to the operation of the machine.

13. In a machine of the class described, the combination of a totalizer comprising a plurality of registering elements, type carriers adapted to print items entered on the totalizer, means for resetting the registering elements to zero and setting the amounts thereon on the type carriers, and additional type carriers operated directly by the registering element of highest denomination for printing totals together with the first mentioned type carriers.

14. In a machine of the class described, the combination of a main operating mechanism, a plurality of totalizing elements, type carriers for printing items entered on the totalizing elements, means for resetting the totalizing elements to zero and operating the type carriers accordingly, additional type carriers operated directly by the totalizing element of highest order and adapted to print totals together with the first mentioned type carriers, means for preparing the machine for total printing operations, and means operated by said preparing means for restoring the additional type carriers to zero position.

15. In a machine of the class described, the combination of a main operating mechanism, a plurality of totalizing elements, type carriers for printing items entered on the totalizing elements, means operated by the main operating mechanism for resetting the totalizing elements to zero and setting the amount thereon on the type carriers, additional type carriers operated directly by the totalizing element of highest denomination and adapted to print totals together with the first mentioned type carriers, means operable to prepare the machine for total printing operations and to reset the additional type carriers to zero position after the machine has been operated, and means compelling operation of the machine to print the total after the preparing means has been operated before the additional type carriers can be reset.

16. In a machine of the class described, the combination of a totalizer, comprising a plurality of registering elements, type carriers, one for each registering element, means for operating the registering elements and the type carriers in item entering operations, and for setting the amounts on the registering elements on the corresponding type carriers in total printing operations, additional type carriers operated by the registering element of highest denomination and adapted to print totals together with the first mentioned type carriers, and impression means

adapted to print only from the first mentioned type carriers to record items, and from the first mentioned type carriers and the additional type carriers to print totals.

5 17. In a machine of the class described, the combination of a totalizer, type carriers for printing items entered on the totalizer and part of the totals thereof, additional type carriers for printing amounts of highest de- 70
10 nominations in the totals entered on the totalizer, impression means adapted to co-
operate with the face of the type carriers and constructed to print only from the first men-
15 tioned type carriers in item entering opera-
tions, and from the first mentioned and the additional type carriers in total printing opera-
20 tions, and means for preparing the ma-
chine for total printing operations and pre-
paring the impression means to print from
25 the first mentioned type carriers and the additional type carriers when a total is
printed.

18. In a machine of the class described, the combination of a main operating mechanism, 25 a totalizer, type carriers for printing items entered on the totalizer and part of the totals thereon, additional type carriers for print-
30 ing amounts of highest denominations in the totals entered on the totalizer, impression
35 means constructed to print only from the first mentioned type carriers in item enter-
ing operations, and from the first mentioned type carriers and the additional type carriers in total printing operations, means operable
40 preliminarily to the operation of the machine for preparing the machine for printing a total, said means operating to effect an ad-
justment of the impression means to print from the additional type carriers and the
45 first mentioned type carriers.

19. In a machine of the class described, the combination of a main operating mechanism, a totalizer, type carriers for printing items entered on the totalizer and part of the totals thereof, additional type carriers for printing amounts of highest denominations in the totals on the totalizer, impres-
45 sion means having a cut away portion nor-
mally under the additional type carriers
50 so that the latter do not print during item entering operations, and means operable
preliminarily to the operation of the ma-
chine in printing a total, for operating said
55 impression means to carry the cut away por-
tion from under the additional type carriers.

20. In a machine of the class described, the combination of a main operating mechanism, a totalizer comprising a plurality of registering elements, type carriers, one for
60 each registering element, adapted to print items entered on the totalizer and the
amounts standing upon the registering ele-
ments, differential mechanism for operating
the type carriers and registering elements in
65 adding operations, and resetting the regis-
tering elements to zero, and operating the type carriers accordingly in total printing operations, additional type carriers operated directly by the registering element of highest denomination in adding operations, and
70 adapted to print totals together with the first mentioned type carriers, an impression device for printing from the first mentioned type carriers in adding operations, and the first mentioned and additional type carriers 75 in total printing operations, manually oper-
able means moved from a normal position for preparing the differential mechanism to restore the registering elements to zero posi-
80 tion, and for adjusting the impression de-
vice to print from the first mentioned type carriers and additional type carriers, and means operated by said manually operable means when the latter is restored to normal position, for turning the additional type 85 carriers to zero position.

21. In a machine of the character set forth, the combination of a keyboard, de-
nominalional totalizer elements controlled thereby to register items set up on the key- 90
board, printing elements to list the several items set up on the keyboard and also adapt-
ed to print totals, and a combined totalizer and printing element adapted to register digits of an order higher than the first men-
95 tioned totalizer elements, and constructed to print in alignment with the printing effected by the first mentioned printing elements in a total printing operation.

22. In a machine of the character set 100
forth, the combination of a keyboard, de-
nominalional totalizer elements controlled thereby to register items set up on the key-
board, printing elements to list the several amounts set up on the keyboard, means to 105
cause the printing elements to print a total of the amount registered on the totalizer elements, under the control of such totalizer elements, and a combined totalizer and printing element adapted to register the 110
number of times the capacity of the totalizer element of highest denomination has been exceeded, and to print its indication along-
side the amount impressed upon the record by the printing elements, in a total printing 115
operation.

23. The combination of an actuating rack member, a driving member therefor, means for connecting said members, a member yieldably movable with one of said first mentioned members in spaced relation to said connecting means, and means for ar-
resting said last mentioned member to permit the connecting means to contact there-
with to disconnect the rack and driving 120
members.

24. The combination of a totalizer, a totalizer actuator, driving means for the actuator, a latch connecting the actuator to the driving means, means for operatively con- 125
130

- necting the totalizer with the actuator to resetting purposes to move said actuator 30
drive the totalizer forwardly for accumulating and reversely for resetting it to zero, and latch breaking control means positioned
5 into cooperative relation with the totalizer by the totalizer-actuator connecting means as it is moved into position to connect the totalizer with the actuator for resetting movement.
- 10 25. The combination of a totalizer, an actuator, a slidably mounted coupling pinion, means for sliding said pinion into position to couple the totalizer with the actuator for driving the totalizer forwardly and reverse-
15 ly, a slidably mounted totalizer-actuated actuator-controlling means, means for moving said coupling pinion into position to drive the totalizer reversely, and means movable with said coupling pinion for mov-
20 ing the actuator-controlling means into functioning position with respect to said totalizer.
26. The combination of an actuator, a totalizer, a pivotally supported pinion for
25 connecting the totalizer with the actuator for accumulating and resetting purposes, a slidably mounted actuator control, and means movable with said pinion as it moves to connect the totalizer with the actuator for
- 30 control means into cooperative relation with said totalizer.
- 35 27. The combination of a totalizer, an actuator, driving means therefor, a latch connecting the actuator with the driving means, a pivoted means for breaking the latch, a pivoted means for coupling the totalizer to the actuator for resetting purposes, a slidable means adapted to be moved upon movement of said pivoted coupling means, into position to be actuated by said totalizer as it is reset, and a connection between said slid-
40 able means and said pivoted latch breaking means for moving the latter upon actuation of said slidable means by the totalizer. 45
- 45 28. In a machine of the character described, the combination of manipulative means; a totalizer controlled by the manipulative means to accumulate items; printing elements to list the items so accumulated, and adapted to print certain denominational orders of a total; and additional printing elements directly operated by the totalizer of highest order to register and print digits of an order higher than that of the highest 50 order totalizer to complete the total. 55

In testimony whereof I affix my signature.
JOHN A. WERNER.
